(57) **CLAIM**

The ornamental design for an eyebrow spoolie and spatula tool, as shown and described.

DESCRIPTION

FIG. 1 is a perspective upright view of one embodiment of our eyebrow spoolie and spatula tool.

FIG. 2 is a front view of the eyebrow spoolie and spatula tool shown in FIG. 1.

FIG. 3 is a back view of the eyebrow spoolie and spatula tool shown in FIG. 1.

FIG. 4 is a view from the right of the eyebrow spoolie and spatula tool shown in FIG. 1.

FIG. 5 is a view from the left of the eyebrow spoolie and spatula tool shown in FIG. 1.

FIG. 6 is an enlarged top end view of the eyebrow spoolie and spatula tool shown in FIG. 1; and,

FIG. 7 is an enlarged bottom end view of the eyebrow spoolie and spatula tool shown in FIG. 1.

Portions of the embodiments of our eyebrow spoolie and spatula tool shown in FIGS. 1-7 shown in dashed lines form no part of the claimed invention.
